UNITED STATES PATENT OFFICE.

MICHEL POIRRIER, OF ST. AMELIA, LOUISIANA.

JOURNAL-BEARING FOR CARS.

SPECIFICATION forming part of Letters Patent No. 761,903, dated June 7, 1904.

Application filed September 10, 1903. Serial No. 172,680. (No model.)

To all whom it may concern:

Be it known that I, MICHEL POIRRIER, a citizen of the United States, residing at St. Amelia post-office, in the parish of St. James and State 5 of Louisiana, have invented certain new and useful Improvements in Journal-Bearings for Cars; and I do hereby declare the following to be a full, clear, and exact description of the invention, such as will enable others skilled 10 in the art to which it appertains to make and use the same.

My invention relates to improvements in journal-bearings for cars or other like vehicles.

It consists of certain improvements in means 15 for lubricating the journal-bearings and for preventing the access of dust, grit, or the like to the same and also to keep the said journal-bearings from heating when in use.

My invention will be understood by reference 20 to the accompanying drawings, in which the same parts are indicated by the same letters throughout the several views.

Figure 1 is a vertical section through the car-wheel and journal-box and shows the axle 25 in elevation. Fig. 2 is a section along the line 2 2 of Fig. 1, parts of the inner face of the journal-box being broken away. Fig. 3 is an end view, and Fig. 4 a plan, of the invention.

A represents a car-axle having the usual 30 skein or bearing. On the axle the wheel B is secured in the usual way, and the said skein supports the usual bearing-blocks, as shown in Fig. 1.

C represents the journal-box, above which 35 the car-springs (not shown) are secured, which box is preferably flanged, as at c, to which flanges the water-compartment D is secured, as by suitable bolts d. The journal-box C is provided with an overflow - passage e, controlled by a faucet e', and it is also provided with a filling-pipe F, preferably closed by a cap f. The compartments C and D are connected by the pipe H, which may be closed by the cock h. The top of the compartment D 40 is closed, preferably, with a screw-plug g. The inner head C² of the journal-box has attached thereto a slotted plate C³, which slips over the axle and in which travels the two shutters i and i', which are provided with projecting arms i², which are connected together.

by the springs i, which springs are so adjusted as to keep the shutters i and i' tightly against the periphery of the axle A and prevent the escape of the lubricant from the journal-box. The plate C³ is secured to the head 55 C² of the journal-box by means of the bolts e². (Shown in dotted lines in Fig. 2.) In practice the operation of the device is as follows: The parts being in the position shown in Fig. 1, with the cap f removed from the pipe F, 60 water is poured into the box C until it begins to overflow through the outlet e. Then the faucet e' is closed, and the box C is filled with oil until the oil rises up in the pipe F. Now unscrew the plug g and fill the water-compartment 65 D with water. Then open the cock h, which will normally be left open except when refilling the journal-box with lubricant. It will be seen that the upper part of the skein of the axle will be immersed in oil and the 70 lower part in water, and the water from the compartment D will flow in past the cock, compensating for any unavoidable waste of fluid in the journal-box, and thus rendering it only necessary to fill up the journal-box 75 with lubricant at long intervals. By using oil on top of the skein and water beneath, as shown, the parts are kept well lubricated and also washed clean, and, moreover, the water cools off the journal-bearings and prevents "hot 80 boxes." A small hole should preferably be provided in the top of the cap f, as shown in Fig. 4, to allow of the escape of any steam that may be formed if the friction should by any accident become excessive. The shutters 85 should be lubricated preferably with some thick gum lubricant as a further protection against the escape of fluid from the journal-box. In cold weather instead of water a mixture of water and glycerin may be used. As 90 is well known, such a mixture will not freeze except under extremely low temperatures, such as are not ordinarily experienced in the United States or its Territories.

I do not mean to confine the invention to 95 the precise details of construction, as various modifications might be made which could be used without departing from the spirit of my invention.

Having thus described my invention, what 100

I claim, and desire to secure by Letters Patent of the United States, is—

1. In a journal-bearing for the axles of cars or the like vehicles, the combination with a water-tight journal-box adapted to inclose the skein of the axle, and a supply-compartment for the water connected thereto, said compartment extending above the top of the journal-box and opening into said box near its base, of means for feeding oil to the top of said box, and means for preventing the escape of fluid therefrom, substantially as described.

2. In a journal-bearing for the axles of cars or like vehicles, the combination with a closed journal-box, of means engaging the axle and preventing the escape of fluid from said box, a water-compartment provided with a connecting-pipe opening into said box, a cock controlling said opening, and means for feeding oil and water to said box, substantially as described.

3. In a journal-bearing for the axles of cars or the like vehicles, the combination with a water-tight journal-box adapted to inclose the skein of the axle, and a supply-compartment for the water connected to said box, said compartment extending above the top of the journal-box and opening into said box near its base; of means for feeding fluid to the top of said box, and means normally engaging the axle and preventing the escape of fluid therefrom, substantially as described.

4. In a journal-bearing for the axles of cars or like vehicles, the combination with a closed journal-box, a guard engaging the axle and preventing the escape of fluid from said box, and a water-compartment provided with an opening into said box near its base and extending above the top of said box, of means for feeding oil and water to said box, substantially as described.

5. In a journal-bearing for the axles of cars or like vehicles, the combination with a closed journal-box, and a guard engaging the axle and preventing the escape of fluid from said box, of a water-compartment secured at the outer end of said box and projecting above the same and provided near its bottom with an opening into said box, a cock controlling said opening, and means for feeding oil and water to said box, substantially as described.

6. In a journal-bearing for the axles of cars or the like vehicles, the combination with a water-tight journal-box adapted to inclose the skein of the axle, of a supply-compartment for the water connected to said box, an outlet to the air provided at some distance above the bottom of said box, with means for closing same when desired, and means for feeding fluid to said box, substantially as described.

7. In a journal-bearing for the axles of cars or like vehicles, the combination with a closed

journal-box, and a guard engaging the axle and preventing the escape of fluid from said box, of a water-compartment secured at the outer end of said box and projecting above the same and provided with an opening into said box near its base, and means for feeding oil and water to said box, substantially as described.

8. In a journal-bearing for the axles of cars or like vehicles, the combination with a closed journal-box, a guard engaging the axle and preventing the escape of fluid from said box, of a water-compartment secured at the outer end of said box and projecting above the same and provided with an opening into said box near its base, a cock controlling said opening, and means for feeding oil and water to said box, substantially as described.

9. In a journal-bearing for the axles of cars or the like vehicles, the combination of a water-tight journal-box adapted to inclose the skein of the axle, a supply-compartment for the water connected thereto and extending above said box, and an inlet-pipe in the top of said box and opening into said box near its base for feeding fluid to said box, substantially as described.

10. In a journal-bearing for the axles of cars or the like vehicles, the combination of a water-tight journal-box adapted to inclose the skein of the axle, a supply-compartment for the water connected thereto and extending above said box, and an inlet-pipe in the top of said box and opening into said box near its base for feeding fluid to said box, and a guard for preventing the leakage of fluid along the axle, substantially as described.

11. In a journal-bearing for the axles of cars or like vehicles, the combination with a closed journal-box, a guard engaging the axle and preventing the escape of fluid from said box along the axle, a water-compartment secured at the outer end of said box and projecting above the same and provided with an opening into said box near its base, and an inlet-pipe in the top of said box, and provided with a perforated cap, substantially as described.

12. In a journal-bearing for the axles of cars or like vehicles, the combination with a closed journal-box, a guard engaging the axle and preventing the escape of fluid from said box along the axle, a water-compartment secured at the outer end of said box and projecting above the same and provided with an opening into said box near its base, a cock controlling said opening, and an inlet-pipe in the top of said box, substantially as described.

In testimony whereof I affix my signature in presence of two witnesses.

MICHEL POIRRIER.
